SIGNORS TO ANTHONY COMPANY, OF STREATOR, ILLINOIS, A CORPORATION OF
ILLINOIS.

DUMPING BODY.

Application filed February 9, 1926. Serial No. 87,184.

This invention, which is in part a continuation of applicant's application No. 81,911, filed January 18, 1926, relates to a tipping receptacle and particularly to a tipping receptacle or body as applied to a vehicle. In the form here illustrated the invention is embodied in a dumping body for an automobile truck, although it might be embodied in many other forms. One of the objects of 10 the invention is to provide a device whereby the body may tip and when tipped moves bodily with respect to its support a distance greater than that which is due to the tipping motion alone. Another object is to provide 15 in connection with such a body means for moving the body during the tipping a distance greater than the projection of the rocker which carries the body upon its support. Another object is to provide such a 20 motion without the use of additional moving mechanisms. Other objects will appear from time to time throughout the specification and claims.

Our invention is illustrated diagrammatically in the accompanying drawings, where- 25 in:

Figure 1 is a side elevation of the body in the loading or upright position;

Figure 2 is a similar view showing the 30 body in the tipped position;

Figure 3 is a vertical cross section on an enlarged scale taken on line 3-3 of Figure 1;

Figure 4 is an inverted plan view of one of 35 the rockers showing a modified form of the roller arrangement;

Figure 5 is a generally similar view to Figure 1 showing a modified form of the body moving means in which the track along 40 which the body moves is substantially horizontal.

Figure 6 is a vertical cross section on an enlarged scale taken on line 6-6 of Figure 5.

Figure 7 is a side elevation of a modified 45 form generally similar to that shown in Figure 5 but with the body supporting cam inverted;

Figure 8 is a side elevation with the body 50 in the tipped position with parts broken away.

A is the frame of the vehicle. A¹ A¹ are 55 springs supporting axles A² A² on which are mounted wheels A³ A³. A⁴ represents the hood within which a driving engine is

mounted. A⁵ is the driver's seat. A⁶ is the steering column and A⁷ the steering wheel. The several parts of the vehicle will not be described in full detail as they form no particular part of the present invention, which 60 may be applied to any type of vehicle whether the same is automotive or not.

B B are supporting tracks each provided with a laterally extending flange B¹ B¹. They are supported at their rear ends by 65 generally vertical members B² B² which are carried from a cross channel member B³ which itself is supported from the vehicle frame A by U-bolts B⁴. B⁵ is a cross member preferably of channel section and resting 70 on the members B², fastened at its ends to the tracks B B adjacent their rear ends to space and tie them in proper spaced relation. B⁶ is a cross member of channel section extending across the vehicle body fastened to 75 it by means of U-bolts B⁷. The forward ends of the track members B are supported on the cross member B⁶.

C is the vehicle dumping body. It is mounted on a sub-frame C¹ which is formed 80 preferably of channel members as shown. At its rear the body is provided with a swinging gate C² which is normally held in the closed position by a latch C³ which is provided with a spring C⁴ to hold it in the 85 locking position. C⁵ is a chain fastened to the rear of the vehicle body at C⁶ and of such length that when the body approaches its full tipped position, the chain becomes taut and moves the latch to permit the gate to swing open.

D D are cam shaped rocker members fastened to the frame C¹ of the body C, and each of them is provided on its curved or cam face with a plurality of rollers D¹. The curved 90 faces of the rockers rest upon and are in contact with the flanges B¹ of the track members B. The rollers are so positioned that when the body is in the upright or loading position as shown in Figure 1, none of the rollers is in contact with the track but almost immediately after the start of the dumping or tipping movement the first roller is brought in contact with the track and thereafter the rollers only are in contact with 100 the track and no solid or immovable part of the rockers is in contact with the track. D² is a supporting member fastened to the rockers and extending across from one to the other. This member serves additionally to 105 110

space the rockers and hold them in proper spaced relation, and also when the body is in the upright position as shown in Figure 1, it comes in contact with the upper part of each of the track members, B, and these carry all or part of the load of the body in this position, and thus reduce the weight carried by and the strain upon the flanges B¹ of the tracks.

10 E E are guiding members or channels situated one on either side of the vehicle adjacent its rear end. They are held against movement and are positioned as shown at an angle to the horizontal, and flare outwardly and upwardly—that is to say the size of the channel is larger at the top than at the bottom. At the top of each a downwardly depending portion E¹ is formed. These channel members are supported by 15 upwardly extending straps E² E³. E⁴ E⁴ are rollers one of such rollers being mounted adjacent the upper end of the curved portion of each rocker and extending outwardly beyond the rocker and lying within the channel member E.

20 In Figure 4, there is shown a modified form of rocker in which the rocker member is formed of a pair of side members F F within which are mounted a plurality of narrow rollers F¹ F¹ these rollers being staggered with relation to each other.

25 G is one member of a supporting leg or prop. G¹ is a co-operating member of such prop. The members are free to rotate with relation to each other in one direction, and are held against rotation beyond a given limit in the opposite direction by means of the stop G² on the member G¹. G³ is a pivot in which the bottom end of the member G is carried. It terminates in a downwardly extending shank G⁴ which passes through a member G⁵ and is free to move with relation to it. G⁶ is a helical spring about a shank G⁴ and it is confined and held in 40 position by a nut and washer G⁷, G⁸. G⁹ is a cable or chain by means of which the prop may be broken to permit the body to return after tipping has been completed.

45 In Figures 5 and 6 there is illustrated a modified form. In this form the rockers are made preferably of plates H H which are mounted on the bottom of the body C and fastened to the body frame C¹. Rollers H² similar to the rollers D¹ in the other form of the device are mounted between the plates H H.

50 Track members I, having outwardly extending lateral flanges I¹ are mounted in a generally horizontal position and carried at their rear ends on the cross member I² supported from the body frame A and bolted to it by means of bolts I³. At its forward ends the track members are carried by a cross member I⁴.

55 J J are channel members generally similar

to the channel members E described above. They are positioned, however, inside of the rocker members in the form shown in Figures 5 and 6 and are fastened to and supported from the track members I I. Each of them is wider at its top than at its bottom, which is provided with a downwardly curved portion J¹ at its top.

60 K K are rollers carried in supports K¹ K¹ which are fastened to channel members K² K² which are themselves fastened to the body frame and in effect form part of the sub frame or stiffening structure of the body.

65 In the forward end of the body frame C¹ is a contact portion L with which the nose L⁴ of the latch engages. L¹ is a stop supported from the vehicle frame A and adjacent the forward end of the tracks. Fasted preferably to it is a pivot member L² to which the locking latch member L³ is pivoted. This member is provided with a latch point or nose L⁴ and is normally held in locking position by means of the spring L⁵. The latch is provided with an operating handle L⁶. When it is depressed the latch nose is moved out of contact with the portion L and the body is free to tip. The spring L⁵ normally holds the latch in locking position and when the body returns to the upright position, it will automatically be latched.

70 The form shown in Figures 7 and 8 is generally similar to that shown in the other figures except that the cam which supports the body on the vehicle is inverted. The supporting frame M is carried on cross members I² and I⁴ in the same manner as is the track I shown in Figure 5.

75 The mechanism for supporting the body at its forward end is the same and the latch mechanism is the same as that shown in the other figures described above. The body itself is the same as that described above. It is provided with a sub frame X having a laterally extending flange X¹ which forms in effect a track, but in this case the cam is not mounted on the body. In place of the construction shown in the other figures, a pair of cams N is fixedly mounted on the frame work M. Each of these cams is provided adjacent its top with a generally flat portion N¹ upon which the body rests when in the upright position shown in Figure 7. Joining the cams and extending across between them is an angle member N² which to some extent supports the body when the latter is in the upright position. The cams are curved as shown and carry in their curved face a plurality of rollers O. As the body tips, the track portion X¹ of the frame X comes in contact with the rollers O and the body is free thus to slide down along the curved cam track members, being thus in contact with the rollers.

80 P is a channel generally similar to the

channels J and E shown in the other figures. It is provided with an inwardly turned point or flange P¹ and is slightly curved at its bottom end as at P².

5 A roller Q is mounted on the body and lies and rides within the channel member. The operation of these parts is the same generally as that described above in connection with corresponding parts. The roller and 10 channel section each cause the body to move rearwardly and downwardly along the fixed cam as the body tilts.

Although we have shown an operative device, still it will be obvious that many 15 changes might be made in size, shape and arrangement of parts without departing materially from the spirit of my invention; and we wish, therefore, that our showing be taken as in a sense diagrammatic.

20 The use and operation of our invention are as follows:

As shown herewith in the several forms of the invention it is applied particularly to a dumping body in which the body itself is mounted so that the combined weight of the 25 load and the body are out-of-balance. Thus as soon as the body is freed to tip by unlatching the latch, it automatically moves to tip itself. As soon as the body has tipped 30 very slightly the first or lowest roller of the rocker support comes in contact with the track and at practically the same time the channel engaging rollers E⁴, for example, come in contact with the bottom flanges of 35 the channels E. Thus further tipping movement would be prevented except for the fact that the rollers permit the body to be drawn rearwardly as it tips, and thus as the body continues to tip, bringing successive rollers 40 in contact with the flanges of the track, the rollers E⁴ run downward and backward along the lower flanges of the channels E and pull the body bodily to the rear. Thus 45 the body during its tipping is drawn bodily to the rear a distance greater than the projection of the rockers upon the track. One 50 result of this is that the body is moved far enough to the rear so that it may tip over the vehicle frame at the end of its dump a degree sufficient to have a satisfactory angle 55 of inclination.

As the body moves to the dumping position the supporting leg or legs, made up primarily of the parts G and G¹, assume a generally straight position, and as they finally snap into position prevent return movement 60 of the body. The springs G⁴ permit the pivotal support member G³ to be raised from its position and thus they furnish a cushioning and shock absorbing mechanism which is effective as the body reaches the extreme limit of the dump. Further, at approximately the time the body reaches its full tipped position, the chains or chain controlling 65 the gate latch or latches become taut

and operate to open the latch automatically. Thus as the body completes this movement of the dumping position, it is automatically opened and the load slides out.

The body has a strong automatic tendency 70 as soon as it is free of the load to move back to the original or upright position. This is resisted by the supporting leg or legs or braces, and when the body is to be brought back, these legs are broken by pulling the 75 chain G⁹ and the body is then free to return to its normal position.

For some purposes the body and its supporting mechanism may be so designed and proportioned that the body will automatically return to its upright position as soon as it is free to do so. For other purposes it may be designed so that it requires a mechanism which may be power or manually operated to cause returning movement. The 80 particular details of the body tipping and righting mechanisms form no particular part of the present invention, and the invention is not limited to the particular application 85 shown.

90 In the form shown in Figures 7 and 8 the relation of the parts is generally the same as that shown in the other figures and their operation is generally the same. The cam with the rollers in its face is placed on the vehicle sub-frame and is fixed. The body moves with relation to the cam. As the body moves it is caused to move rearwardly along the cam and thus it is true of this form just as it is of the other forms that as 95 the body tips, it moves a distance greater than would normally be due to the tipping alone.

100 We claim:

1. In combination, a support and a body movable with relation thereto having a supporting part adapted of itself to tip the body, and a separate guiding element for such body adapted to cause it to move longitudinally a distance greater than that normally incident to the tipping alone. 110

2. In combination, a support and a body movable with relation thereto and having a supporting part adapted of itself to tip the body, a supporting track and a separate guiding element for said body adapted to cause it to move longitudinally a distance greater than that normally incident to the tipping alone. 115

3. In combination a support and a body movable with relation thereto and having a supporting part adapted of itself to tip the body, and a separate guiding element for said body, a member engaging said guiding element and with such element adapted to cause it to move longitudinally a distance greater than that normally incident to the tipping alone. 120

4. In combination a track, and a body supported from said track and movable with 130

relation thereto, supports adapted of themselves to tip the body with relation to the track, and adapted to move longitudinally with relation to the track, a member on such body, guiding elements engaged by such member and adapted to cause the body to move a distance greater than that normally incident to the tipping alone.

5. In combination a track, and a body supported from said track and movable with relation thereto, supports adapted of themselves to tip the body with relation to the track, and adapted to slide with relation to the track, guiding elements adapted as the body tips to cause it to move a distance greater than that normally incident to the tipping alone.

6. In combination a track, and a body supported from said track and movable with relation thereto, supports adapted of themselves to tip the body with relation to the track and adapted to slide with relation to the track, a projection on such body, guiding elements engaged by such projection and adapted as the body tips to cause it to move rearwardly a distance greater than that normally incident to the tipping alone.

7. In combination a track, a body supported from said track and movable with relation thereto, supports adapted of themselves to tip the body with relation to the track and adapted to slide with relation to the track, a projection on such body, fixed guiding elements mounted on the vehicle, engaged by such projection and adapted as the body tips to cause it to move rearwardly a distance greater than that normally incident to the tipping alone.

8. In combination with a vehicle, a track fixed on said vehicle, and a body supported from said track, and movable with relation thereto, supports on the body resting on the track, adapted of themselves to tip the body with relation to the track and adapted to slide with relation to the track, guiding elements adapted as the body tips to cause it to move rearwardly a distance greater than that normally incident to the tipping alone.

9. In combination with a vehicle, a track member on said vehicle, a body supported from said track and movable with relation

thereto, curved supports on the body supported from the track, and adapted of themselves to tip the body with relation to the track, such supports provided in their contact faces with rollers whereby they are adapted to slide with relation to the track, a projection and a separate guiding element mounted one on the vehicle and one on the body, the guide engaging with the projection, and the two adapted in cooperation as the body tips to cause it as a result of such tipping to move rearwardly a distance greater than that normally incident to the tipping alone.

10. In combination with a vehicle, a track member and a body supported from such track, and movable with relation thereto, curved supports for such body adapted of themselves to tip the body, such supports provided in their contact faces with rollers whereby they are adapted to slide with relation to the track, a projection and a separate guiding element mounted one on the vehicle and one on the body, the guide engaging with the projection, and the two adapted in co-operation as the body tips to cause it as a result of such tipping to move rearwardly a distance greater than that normally incident to the tipping alone.

11. In combination with a vehicle, a track member and a body movably supported with relation to such vehicle, curved supports in contact with such track, and supporting thereby the body, such supports adapted of themselves to tip the body with relation to the track, and being provided in their contact faces with rollers whereby they and the track are adapted to have relative sliding movement, a projection and a separate guiding element mounted one on the vehicle and one on the body, the guiding element engaging with the projection, and the two adapted in cooperation as the body tips to cause it as a result of such tipping to move rearwardly a distance greater than that normally incident to the tipping alone.

Signed at Streator, county of La Salle and State of Illinois, this 4th day of February, 1926.

WILLIAM C. ANTHONY.
